Eindhoven, Netherlands

Application February 7, 1935, Serial No. 5,487
In Germany February 12, 1934

15 Claims. (Cl. 274—46)

This invention relates to the mechanical recording of optically reproducible vibration tracks and to the carriers used for such tracks, and more particularly to the recording of sound vibrations on a carrier, which is preferably a film.

In the known methods of this type of recording the vibration track is produced by removing from a substratum, in accordance with the vibrations to be recorded, parts of a covering layer, sometimes with the removal of portions of the substratum itself, so that a vibration track having width variations, and sometimes also depth variations, is formed. By making the covering layer of opaque material and the substratum of transparent material, or when using transparent material for both the covering layer and substratum, by subsequently blackening either the track surface or the background, constituted by the covering layer, the record so formed can be optically reproduced by means of a photo-electric cell, or photographic prints can be made thereof. To reinforce the carrier, especially in the case of a film, the layer and the substratum are usually applied to a strong base layer made of transparent material, for example of celluloid. In a modification of the said known methods the record is produced on a carrier of which the part intended for the record comprises two adjoining transparent layers one of which is constituted by a material to which a "dyestuff" readily adheres, the second layer, which preferably is the covering layer, being of a material to which the "dyestuff" does not adhere, the base layer, if present, being made of an also transparent material.

The term "dyestuff" as used herein is intended to include all those substances (dyes, inks, etc.), which are capable of bringing about, for the optical reproduction of the record, the desired difference in transparency of the vibration track and of its background and/or which may serve as a printing color.

By the expression "reproduction" as used herein, is meant both a direct reproduction of the vibration track, by means of a photo-electric cell, as well as its photographic copying.

By making the covering layer and the substratum of materials as described, reproduction can be effected in several different ways, depending upon conditions and purpose.

For instance, by treating with a suitable dyestuff the mechanically-recorded record, that is either the vibration track itself or its background, duplicates thereof can be obtained either optically, or mechanically by means of one of the well-

known printing methods, and without requiring special measures, subsequent to the recording, to prevent dyestuff from adhering at such portions of the record where it is not desired.

According to the present invention, the covering layer contains a material which is opaque to red and infra-red rays, i. e., to rays within the range of 7,000 to 20,000 Å, such as for example, copper sulphate. Preferably this layer is furthermore transparent to ultra-violet rays (from 10,000—4,000 Å) just as the other layers, which the carrier may be possessed of. The latter being moreover transparent to infra-red rays in this case. The symbol "Å" as used above represents 15 Ångstrom units, i. e. a unit of length equal to one ten-thousandth of a micron, or 10^{-8} centimeters. If now the covering layer is made of a dyestuff-repelling material and the cutting or intermediate layer is made of a material which has 20 dyestuff-retaining properties and which is transparent to red and infra-red rays, whereas the base layer, which is usually made of celluloid, is also transparent to red and infra-red rays, there are various possibilities. 25

The direct reproduction of the record immediately after it has been recorded (play-back) by means of a photocell, a light source, occasionally combined with a suitable filter, producing only red and infra-red rays, and the usual optical or 30 light-slit, requires no treatment of the record with a dyestuff. As the maximum sensitivity of present-day photocells is in the red and infra-red range, the red-opaqueness of the background is sufficient to obtain its desired contrast with 35 the track.

However, for the printing of copies from the record, light having its greatest actinism within the range of 3,000 Å to 4,000 Å, is used. When both the covering layer and the intermediate layer 40 (and also the base layer) are transparent to such rays, before making prints of the record, the track is rendered opaque to such light by a suitable dyestuff which, however, does not need to be a 45 printing color.

Most dyestuffs are suitable for this purpose, the only claim to be fulfilled being that it is opaque to violet and ultra-violet light rays. For instance nigrosine may be used. 50

A special advantage can be obtained, if a dye stuff is chosen, which besides being opaque to violet and ultra-violet rays is moreover transparent to red and infra-red rays. In this case the original track remains readily reproducible. 55

As a specimen of such a dye "red for dark room light" can be mentioned. This may be understood more clearly by the fact that the methods of the present invention can be advantageously combined with so-called "noiseless" sound recording. The so-called "noiseless" sound records can be obtained during the recording, copying or reproduction, if measures are taken to so limit the transparent portions of the record that the reproduction is subjected only to the influence of the amplitude variations and not to that of the particles of dirt or scratches present at the transparent portions.

If the original sound-record is "noiseless" the reproduction of the original record or of a copy thereof is "noiseless", if only the track itself transmits the light during reproduction.

Furthermore it is proposed to obtain the contrast in the adhering properties of the two layers by forming one layer of tanned gelatin and the other of untanned gelatin. If tanned gelatin is treated with water it adheres fatty colors, but in the contrary repels aqueous colors. Untanned gelatin has just the reversed properties. It repels fatty colors, but adheres aqueous colors.

Several possibilities for mechanical printing are present now:

Example 1.—The covering layer is formed of tanned gelatin and the intermediate or cutting layer is formed of untanned gelatin:

A. For printing a fatty color is used: a print is obtained, which is readily reproducible.

B. For printing an aqueous color is used: a dia-positive is obtained from which by optical reprinting readily reproducible prints can be obtained.

Example 2.—The covering layer is formed of untanned gelatin, whereas the intermediate or cutting layer is formed of tanned gelatin:

A. For printing a fatty color is used: a dia-positive is obtained from which by optical reprinting readily reproducible prints can be made.

B. For printing an aqueous color is used: a print is obtained which is readily reproducible. It will be clear of course that the above mentioned carriers treated with a dyestuff can be also used for making photographic prints. The same number of possibilities are present and it is superfluous to recall them therefor. They can be readily deducted from the mentioned examples by replacing

50 B for A and A for B.

In order that the invention may be more clearly understood and readily carried into effect, it will be more fully explained with reference to the accompanying drawing in which:

55 Figure 1 is an enlarged cross-sectional elevation of a carrier according to the invention, including the cutting tool used for the recording.

Fig. 2 is a cross-sectional side view of Figure 1 showing the vibration track as cut by the cutting tool.

60 Figs. 3, 4 and 5 are plan views of films according to the invention, showing different modifications.

Referring to Figs. 1 and 2, the carrier consists of a relatively sturdy base layer 4, for instance of celluloid, of a substratum or cutting layer 3 into which the vibration track is cut, and of a thin covering layer 2 which is non-transparent to red and infra-red light rays and preferable transparent to violet and ultra-violet rays and which is removed at portions corresponding to the vibration track. The layers 2 and 3 may be either dyestuff-retaining or dyestuff-repellent as fully set out above, but in every case the subsequent layers 75 must have opposite properties. The layers 3 and

4 are both transparent to red and infra-red rays and preferably also transparent to violet and ultra-violet rays.

A cutting tool 1 is provided for recording the sound vibrations and is vibrated perpendicularly to the surface of the carrier in agreement with the vibrations to be recorded. As the amplitudes of vibration of the cutting tool are very small at high frequencies, and as it is essential, for satisfactory reproduction, that a minimum amplitudinal variation of the vibration track be obtained, the cutter is provided with V-shaped cutting edges 5, which form with each other an angle α of about 174° . Due to such slope of the cutting edges quite small movements of the cutting tool 15 are converted into large width variations of the vibration track being cut, and in addition to these width variations, depth variations are also formed. As a result of this, recording of the track as shown for example in Figs. 2 and 3, is 20 obtained.

If the covering layer 2 is made of a dyestuff-retaining material and the cutting layer 3 is made of a dyestuff-repellent material, the film, after being colored with a printing color, has the appearance as indicated in Fig. 4, in which the colored portions are shown cross-hatched. A record treated in this manner is suitable, without additional means, for mechanical multiplication by means of one of the well-known printing 30 methods.

If dye is used instead of a special printing color, the record may be either optically reproduced by means of a photocell, or, as is the usual case, may be photographically multiplied, i. e., 35 one or more photographic copies may be made. A record formed and treated in this manner has the additional advantage that when it is to be used for direct optical reproduction, it is possible to determine after the recording, which dyestuff 40 is best suited to obtain a coloring layer having the desired light absorption with regard to the luminous rays used in reproduction.

When the covering layer 2 is made of dyestuff-repellent material and the cutting layer 3 is made of dyestuff-absorbing material, the carrier, after being cut and treated with the dyestuff, appears as shown in Fig. 5, in which the colored portion (now corresponding to the vibration track) is indicated by cross-hatching. The depth of the track is sufficiently small that the color or ink completely fills the track whereby duplicates of the record can be obtained by mechanical printing.

While the duplicates of such records obtained by printing are suitable for optical reproduction 55 by means of a photo-electric cell, they have the drawback that because of the extent of the transparent portion it is difficult to avoid background noise, and therefore it is preferable to photographically duplicate the record so as to obtain 60 copies in which the track is transparent and the background is opaque.

If a vibration track as shown in Fig. 3 is recorded in a "noiseless" manner on a carrier whose covering layer is opaque to red and infra-red rays, 65 the record so formed may be immediately reproduced in a noiseless manner by means of the usual photo-electric cell apparatus. By "noiseless" recording is meant a method of recording in which the central or neutral position of the 70 recording member, for instance the cutting tool, shown in Figs. 1 and 2, is changed during the recording in accordance with the amplitudes of the vibrations being recorded. For instance, when the amplitudes of the vibrations being re- 75

- corded are small, the central position of the above-mentioned cutting tool is raised, whereby the width of the track, and hence the width of the transparent portion between the inwardly-directed peaks of the boundary lines of the track, is reduced. By using a covering layer opaque to red and infra-red rays, the degree to which the record is free from noise can be determined immediately after the recording.
10. By subsequently treating this record with a dyestuff to obtain a record as shown in Fig. 5 the record can be photographically copied, whereby on the copies the track is free from the rustling noise usually present when reproducing film of the type generally used. In addition, copies may be mechanically obtained by means of one of the commonly known printing methods. In this latter case, however, while the record could be used for optical reproduction, the reproduction will not be free from rustling noise, as the track is opaque and its background transparent. To obtain a reproduction free from background noises it is again necessary to make photographic prints of the record.
25. While I have described my invention on hand of specific examples, and for specific applications, I do not wish to be limited thereto, but desire the appended claims to be construed as broadly as permissible in view of the prior art.
30. What I claim is:
1. A carrier for the mechanical recording of an optically-reproducible vibration track, comprising a covering layer of a material opaque to red and infra-red rays, the remaining portion of the carrier being transparent to said rays, and a second layer beneath said covering layer, the material of one of said layers being dyestuff-retaining and the material of the other layer being dyestuff-repellent.
  2. A carrier for the mechanical recording of an optically-reproducible vibration track, comprising a covering layer of a material opaque to red and infra-red rays and transparent to violet and ultra-violet rays, the remaining portion of the carrier being transparent to said rays, and a second layer beneath said covering layer, the material of one of said layers being dyestuff-repellent and the material of the other layer being dyestuff-retaining.
  3. A carrier for the mechanical recording of an optically-reproducible vibration track, comprising a covering layer of a material opaque to red and infra-red rays, the remaining portion of the carrier being transparent to said rays, and a second layer beneath said covering layer, one of said layers being of tanned gelatin and the other layer being of untanned gelatin.
  4. In the manufacture of carriers for the mechanical recording of an optically-reproducible vibration track, the process comprising the steps of forming a layer of a material opaque to red and infra-red rays, forming a second layer of a material transparent to red and infra-red rays, the material of one layer being dyestuff-repellent and the material of the other layer being dyestuff-retaining, and conjoining said layers to form the carrier with said first layer on top.
  5. In the manufacture of carriers for the mechanical recording of an optically-reproducible vibration track, the process comprising the steps; forming a layer of a material opaque to red and infra-red rays and transparent to violet and ultra-violet rays; forming a second layer of a material transparent to violet, ultra-violet, red and

infra-red rays, the material of one layer being dyestuff-absorbent and the material of the other layers being dyestuff-repellent; and conjoining said layers with the first layer on top to form the carrier.

6. In the manufacture of carriers for the mechanical recording of an optically-reproducible vibration track, the process comprising the steps; forming a layer of a material opaque to red and infra-red rays; forming a second layer of a material transparent to red and infra-red rays, the material of one layer being dyestuff-repellent and the material of the other layer being dyestuff-retaining; and conjoining said layers together and to a base layer of a material transparent to red and infra-red rays with the first layer on top.

7. In the manufacture of carriers for the mechanical recording of an optically-reproducible vibration track, the process comprising the steps; forming a layer of a material opaque to red and infra-red rays and transparent to violet and ultra-violet rays; forming a second layer of a material transparent to violet, ultra-violet, red and infra-red rays, the material of one layer being dyestuff-repellent and the material of the other layer being dyestuff-retaining; and conjoining said layers together and to a base layer of a material transparent to red, infra-red, violet and ultra-violet rays with said first layer on top.

8. The method of mechanically recording an optically-reproducible vibration track, comprising the steps; forming a layer of a material opaque to red and infra-red rays; forming a second layer of a material transparent to red and infra-red rays, the material of one layer being dyestuff-repellent and the material of the other layer being dyestuff-retaining; conjoining said layers together and to a base layer of a material transparent to red and infra-red rays with said first layer on top to form a carrier; cutting a vibration track into said first two layers; and treating the carrier with a dyestuff to color only the dyestuff-retaining material.

9. The method of mechanically recording an optically-reproducible vibration track, comprising the steps; forming a layer of material opaque to red and infra-red rays; forming a second layer of a material transparent to red and infra-red rays, the material of one layer being dyestuff-retaining and the material of the other layer being dyestuff-repellent; uniting said layer together and to a base layer of a material transparent to red and infra-red rays with said first layer on top to form a carrier, cutting a vibration track into said first two layers; and treating the carrier with a printing color adhering only to the dye-stuff-retaining material.

10. The method of mechanically recording optically-reproducible vibration tracks comprising the steps; forming a layer of a dyestuff-repellent material opaque to red and infra-red rays and transparent to violet and ultra-violet rays; forming a second layer of a dyestuff-retaining material transparent to red, infra-red, violet and ultra-violet rays; joining said layers together and to a base layer of a material transparent to red, infra-red, violet and ultra-violet rays with said first layer on top to form a carrier; cutting a vibration track into said first two layers; and treating the carrier with an opaque dyestuff to color only the dyestuff-retaining material.

11. The method of mechanically recording optically-reproducible vibration tracks, comprising the steps; forming a layer of a dyestuff-repellent material transparent to violet and ultra-

- violet rays and opaque to red and infra-red rays; forming a second layer of a dyestuff-adherent material transparent to red, infra-red, violet and ultra-violet; uniting said layer together and to a base layer of a material transparent to red and infra-red rays with said first layer on top to form a carrier; cutting a vibration track into said first two layers and treating the carrier to a non-transparent printing color adhering to only the dyestuff-adherent material.
12. The method of mechanically recording optically-reproducible vibration tracks, comprising the steps; forming a layer of a dyestuff-repellent material transparent to violet and ultra-violet rays and opaque to red and infra-red rays; forming a second layer of a dyestuff-adherent material transparent to red, infra-red, violet and ultra-violet rays; conjoining said layers together and to a base layer of a material transparent to red and infra-red rays with said first layer on top to form a carrier; cutting a vibration track into said first two layers; and treating the carrier with a non-transparent printing color adhering only to the dyestuff-adherent material.
13. The method of mechanically recording optically-reproducible vibration tracks, comprising the steps; forming a base layer of a material transparent to red and infra-red rays; joining to one side of said base layer a cutting layer of a dyestuff-adherent material transparent to red, infra-red, violet and ultra-violet rays; joining to the free side of said cutting layer a covering layer of a dyestuff-repellent material transparent to violet and ultra-violet rays and opaque to red and infra-red rays; cutting a vibration track into said covering and cutting layers; and treating

the carrier with a dyestuff transparent to only red and infra-red rays to color only the dyestuff-adherent material.

14. The method of mechanically recording optically-reproducible vibration tracks, comprising the steps; forming a base layer of a material transparent to red, infra-red, violet and ultra-violet rays; joining to one side of said base layer a cutting layer of dyestuff-adherent material transparent to red, infra-red, violet and ultra-violet rays; joining to the free side of said cutting layer a covering layer of a dyestuff-repellent material transparent to violet and ultra-violet rays, and opaque to red and infra-red rays; cutting a vibration track into said cutting and covering layers; and treating the carrier with a printing color transparent to only red and infra-red rays and adhering to only the dyestuff-adherent material.

15. In the reproduction of mechanically recorded and optically-reproducible vibration tracks, the process comprising the steps; forming a layer of a dyestuff-retaining material transparent to ultra-violet and infra-red rays; superimposing on said layer a covering layer of a dyestuff-repellent material opaque to red and infra-red rays and transparent to ultra-violet rays; mechanically recording a vibration track in said layers; reproducing said track by means of a photocell having a maximum sensitivity for red and infra-red rays; treating the layers with an ultra-violet opaque dyestuff which adheres only to the track; and producing a copy by means of ultra-violet light.

JAN HENDRIK DE BOER.
